Attorney

UNITED STATES PATENT OFFICE.

WILLIAM W. SHALLUS, OF LANCASTER, PENNSYLVANIA, ASSIGNOR OF ONE-HALF TO HENRY H. KEEN, OF SAME PLACE.

CAR-DOOR.

SPECIFICATION forming part of Letters Patent No. 291,411, dated January 1, 1884.

Application filed October 10, 1883. (No model.)

To all whom it may concern:

Be it known that I, WILLIAM W. SHALLUS, a citizen of the United States, residing at Lancaster, in the county of Lancaster and State of Pennsylvania, have invented certain new and useful Improvements in Car-Doors, of which the following is a specification, reference being had therein to the accompanying drawings.

This invention relates to certain improvements in freight-cars; and it has for its object to facilitate the moving of the doors of the same, as more fully hereinafter specified.

In the doors of such cars, which are usually constructed to slide in ways or guides at the sides of the cars, during inclement weather the sides of the cars are liable to become coated with ice or sleet, which interferes with the movement of the door; and, again, when the interior of the car is closely packed, the contents have a tendency to bind against the doors and prevent them from being moved.

The object of my invention is to obviate these difficulties, and this I accomplish by the means illustrated in the accompanying drawings, in which—

Figure 1 represents a side elevation of a portion of a car, showing my invention applied thereto; and Fig. 2, a vertical sectional view of the same.

The letter A indicates an ordinary box or freight car. To the sides of the same, at the top and bottom, are secured the brackets B, which are provided with sockets C, in which are pivoted the arms D, the said arms having secured to them the longitudinal rods or guides E. The said rods or guides are intermediately supported by means of an arm, F, pivoted in a recess in the upper portion of the car, at one side. The door, at its vertical edges, top and bottom, is provided with brackets G, which are provided with apertures, and set over the

rods or guides loosely, so that the door may be moved longitudinally thereon.

The letter H indicates a lock-lever fulcrumed to a plate, I, attached to one edge of the door, the said lever being formed with a hooked end, K, which is adapted to "take" into a slot, L, in a plate, M, secured to the car, and bind the car-door closely to the side of the car and hold it thereto. The long arm of the lever is provided with a lateral extension, N, which is slotted, and is adapted to set over the end of a bracket, P, which is provided with an aperture, through which the hasp of a padlock or seal-lock may be inserted to secure the door.

It will be observed that as constructed the guides or bars may be thrown outward from the side of the car, so as to permit the door to work freely in case of the obstructions above mentioned, and that it may be firmly bound upon its seat when closed.

Having thus described my invention, what I claim, and desire to secure by Letters Patent, is—

1. The combination, with a freight-car, of the brackets secured thereto, having sockets in which are pivoted arms carrying longitudinal guide-rods, and the door having brackets adapted to slide thereon, substantially as specified.

2. In combination with the door mounted upon movable longitudinal guides E, the lock-lever H, adapted to bind the door to its seat and lock it thereto, substantially as and for the purpose specified.

In testimony whereof I affix my signature in presence of two witnesses.

WILLIAM W. SHALLUS.
